Specification for Design.

Patented Sept. 20, 1921.

Application filed October 16, 1920. Serial No. 417,518. Term of patent 14 years.

To all whom it may concern:

Be it known that I, CURTIS E. HENDRICKS, a citizen of the United States, residing at Southport, in the county of Marion and State of Indiana, have invented a new, original, and ornamental Design for Ignition-Wire Manifolds, of which the following is a specification, reference being had to the accompanying drawings, forming part thereof.

Figure 1 is a plan view and Fig. 2 a side elevation of an ignition wire manifold, showing my new design.

I claim:

The ornamental design for an ignition wire manifold, as shown.

In testimony whereof I hereto affix my signature.

CURTIS E. HENDRICKS.
